UNITED STATES PATENT OFFICE.

LUKE COONEY, JR., OF KALAMAZOO, MICHIGAN.

TWO-WHEELED VEHICLE.

SPECIFICATION forming part of Letters Patent No. 375,130, dated December 20, 1887.

Application filed May 16, 1887. Serial No. 238,360. (No model.)

To all whom it may concern:

Be it known that I, LUKE COONEY, Jr., a citizen of the United States, residing at Kalamazoo, county of Kalamazoo, State of Michigan, have invented a new and useful Two-Wheeled Vehicle, of which the following is a specification.

This invention relates to vehicles having a body fulcrumed at the forward end to the thills or cross-bar of the thills and supported over the axle by spiral springs; and it has for its object the below-described construction and peculiar association of parts.

In the drawings, forming a part of this specification, Figure 1 is a side elevation with one thill broken away and one wheel removed; Fig. 2, a plan of about one-half the vehicle, and Fig. 3 shows enlarged lettered details in perspective.

Referring to the lettered parts of the drawings, P are the seat bars or body, fulcrumed in the ordinary manner to the thills, or thill cross-bar, if preferred. The spiral springs v have a rearwardly-extended bar, c, attached to the axle, (or other suitable support,) preferably by a shackle, a, and at the inner end of the spiral the spring extends in a bar, c', forward, and then rearward in V shape, or any other suitable form. This latter bar, c', is rigidly attached at suitable points to hold it firmly to the beams i of the body, about in the center, as indicated, by staples, in Fig. 3, so as to fix the springs v horizontally and laterally projecting from the sides of the body P, Fig. 2.

It will be observed that the part of the 35 spring shown at c' is merely for securely attaching and holding the spiral v, and does not in any sense have a spring action beyond the staple S, Fig. 3.

Among the points of utility, aside from the 40 well-known desirable action of spiral springs, may be named simplicity and ease of construction, less strain on the thills, and less danger of the springs breaking.

Having thus described my invention, what 45 I claim is—

1. In combination, the fulcrumed body or seat bars, the axle, and the spiral springs attached to the sides of the body, and having the rear bars shackled to the axle and the forwardly-bent bar rigidly attached to the under side of the body, substantially as set forth. 50

2. In combination, the fulcrumed body, the axle, and the spiral springs at the sides of the body, said springs having the V-bars rigidly attached to transverse beams beneath the body, and having the rear bars shackled to the axle, substantially as set forth. 55

In testimony of the foregoing I have hereunto subscribed my name in presence of two 60 witnesses.

LUKE COONEY, JR.
